ELECTRON APPARATUS FOR HIGH-FREQUENCY PERFORMANCE

Herbert M. Wagner, Asbury Park, N. J.

Application March 5, 1951, Serial No. 213,995

15 Claims. (Cl. 313—70)

(Granted under Title 35, U. S. Code (1952),
sec. 266)

1

The invention described herein may be manufactured and used by or for the Government for governmental purposes without the payment to me of any royalty thereon.

This invention relates to improvements in methods and apparatus for controlling a beam of electrons.

Given two or more beams of electrons from as many different sources but all in the same tube, it has been demonstrated that due to the interaction of the space-charge fields of the respective currents in the beams, or due to interaction between the beams of electrons, it is possible to control one beam by varying the current in an adjacent beam. Examples of electron-discharge devices utilizing this basic principle are to be found in Patent No. 2,229,752 issued January 28, 1941 to Jonker et al. and in Patent No. 2,235,016 issued March 18, 1941 to Andrew V. Haeff. While these devices of the prior art have served a useful purpose, the respective operating characteristics thereof limit their scope of application; as in high-frequency operation.

One of the objects of the present invention resides in the provision of an improved electron-discharge device of the character referred to which has advantages over the various prior construction in the way of adaptability for application to uses wherein the operational frequency reached or maintained can be substantially higher than has been practical or possible heretofore.

Another object resides in the provision of an improved tube of the character referred to wherein there is provision for achieving substantially constant current output and/or transconductance and/or higher transconductance than has been practical or possible with the various methods and constructions proposed heretofore.

Other objects and advantages will hereinafter appear.

In the drawing, the four figures thereof are simplified, schematic, sectional views of various constructions or arrangements and illustrate the operational action in as many different ways or methods of practicing the present invention.

In Fig. 1 of the drawing, the various parts or representations have been designated by the same respective reference numerals designating the same or at least comparative parts or representations in Fig. 3 of the Jonker and Van Overbeek patent aforesaid.

The reference numerals 19 and 5 in Fig. 1 designate any suitable, conventional means, in an evacuated tube 10, for generating the respective spaced, parallel beams or streams 14 and 15 of

2

electrons. Beam 14 may be modulated in intensity by a conventional control grid represented at 14a. On account of mutual repulsion between the two electron beams, changes of or variations in density of the first or controlling beam 14 caused or effected by changes of or variations in the input voltage impressed on grid 14a, effect corresponding deflections of the second or controlled beam 15. Deflection of beam 15 with respect to the bottom edge of a fixed, intercepting plate 15a results in conversion of such deflection into corresponding current changes or variations in current at an associated output plate or electrode 15b. For example, as the current or density in the controlling beam 14 increases, the mutual repulsion between the two beams becomes more pronounced and the controlled beam 15 is deflected accordingly, further away from the blocking or intercepting edge of plate 15a. This action permits more electrons to strike plate 15b whereupon the output current at the latter increases correspondingly. In lieu of plate 15a, an apertured plate may be used. In such case, the size, shape and position of the aperture would be such as to pass substantially the entire beam 15 with the latter directed horizontally in the normal, undeflected position shown.

Beams 14 and 15 may be normally in different planes approximately parallel, at right angles, or at some intermediate angle to each other, and they may be pointed in the same general direction or in opposite directions.

For the purpose of obtaining phase-shift in high-frequency operation, it might be found desirable to shift beam 14 longitudinally with respect to beam 15.

In Fig. 1, the controlling beam 14 is represented as being a relatively narrow, ribbon-type beam. It may, however, be diffused and distributed over a relatively wide area. Other modifications or arrangements would reside in providing for other, additional beams similar to beam 15, all controlled in the same manner as the latter by the single controlling beam 14. To obtain an operational result just opposite to that in Fig. 1, the plate 15a may be constructed so as to block the lower rather than the upper portion of beam 15. This may be done by designing the plate 15a to continue down toward plate 16 and to be provided with an aperture having an edge such that the upper portion of beam 15 is permitted to pass thru to reach plate 15b while the lower portion is blocked. In such case, as the current or density in the controlling beam 14 increases the mutual repulsion between the two beams becomes

more pronounced as before, but the controlled beam 15 is deflected downwardly and toward the blocking or intercepting edge of plate 15a. This action prevents or blocks more electrons from striking plate 15b. The output current at plate 15b is therefore correspondingly less.

The cathodes at 19 and 5 may be at the same or at different potentials. A metallic strip or plate 15c which may be integral with plate 15a, and a similar strip or plate 16, may be supported within the tube and disposed as shown to function as shields against the influence of magnetic fields or other disturbing factors external to the tube. The plates 15a, 15c and 16 may be connected together and be operated at the same potential.

In the arrangement shown in Fig. 2, the beam 14b corresponds to the controlling beam 14 in Fig. 1, and there are two controlled beams 15d and 15e, each of the latter corresponding to the controlled beam 15 in Fig. 1. Supported at the inner edges of beams 15d and 15e are the respective intercepting or blocking plates 15d' and 15e', each of the latter serving the same purpose as the plate 15a in Fig. 1. In operation, as the current in the controlling beam 14b increases the mutual repulsion between beam 14b and the beams 15d and 15e becomes more pronounced and the controlled beams 15d and 15e are deflected accordingly, further away from the plates 15d' and 15e'. This action permits more electrons to strike the respective, associated anode plates 15f and 15g, whereupon the output currents at the latter increase correspondingly.

The respective current outputs at plates 14b', 15f and 15g may be used separately or in combination. If the outputs 14b', 15f and 15g are in parallel, then the transconductance of beam 14b by grid-control at 14a, is augmented by the respective current increments due to the deflection of beams 15d and 15e by beam 14b. Thus, a means or method is provided for obtaining increased transconductance.

With the arrangement in Fig. 2 reversed, i. e., with the intercepting plates 15d' and 15e' located at the outer rather than at the inner edges of beams 15d and 15e, the operational result is just the opposite. In such case, as the current in the controlling beam 14b increases, the mutual repulsion between beam 14b and beams 15d and 15e becomes more pronounced as before, but the controlled beams 15d and 15e are deflected further into the paths blocked by plates 15d' and 15e'. Fewer electrons are then permitted to pass and strike the respective, associated anode plates 15f and 15g. The output currents at the latter therefore become correspondingly lower, and if all outputs are parallel, the transconductance and current charge at plates 15f and 15g subtract from such in beam 14b. This effect might be used to achieve constant current or transconductance by automatic utilization of the same if the current output of beam 14b or the tube transconductance exceeds a specified amount.

Considering another modification in Fig. 2, grids might be added to control the current in beams 15d and 15e, similarly to the grid 14a for controlling the current in beam 14b. Modulation of current outputs of beams 15d and 15e might then be effected by applying voltages to the respective grids for these beams and simultaneously with application of voltage to grid 14a. Modulation of beams 15d and 15e simultaneously would not cause any deflection of beam 14b, whereas modulation of beam 14b causes simul-

taneous deflection and consequent modulation, as explained, of beams 15d and 15e. Thus, isolation of controls is provided which might be useful for converter applications.

By interposing a single screen 17 to function as an accelerating anode and disposed as indicated, adjacent to the sources of beams 14b, 15d and 15e, there is produced the condition of introducing the parallel beams, at equal electron velocities, into an enclosed, screened, field-free region so that deflection (or mutual repulsion) of the beams occurs in proper phase for deflection throughout the entire length of the path, to the respective output plates 14b', 15f and 15g. In other words, throughout the entire length of all beams, the velocity of the electrons is the same, and constant. The electrons, therefore, are always in phase in any vertical plane along and common to the beams so that there is progressive and unidirectional deflection of the controlled beams 15d and 15e throughout their entire length, from source to current-output plate. This in-phase travel of the individual electrons in all beams would be important for operation at high frequency, such as of the order of 200 megacycles or higher. Contrary to this, and as is well known, the prior use of deflecting plates beyond a particular length of beam results in loss rather than gain in deflection-sensitivity. Such loss is attributed to electron phase-differences with respect to the modulating voltage across such deflecting plates.

From the above, it will be apparent that in the electron-beam-repulsion method or arrangement as in Figs. 1 and 2, there can be deflection over a long path with increase in sensitivity, but at no additional increase of circuit-capacity such as would result from lengthening the deflecting plates in a conventional tube design.

In Fig. 2 the individual beams 15d and 15e may be replaced by a single, hollow, cylindrical beam whose longitudinal axis, undeflected, is coincident with that of beam 14b. In such case the source of the cylindrical beam might be an annular or circular ring provided with an emissive surface disposed in a plane perpendicular to the longitudinal axis of beam 14b and with its center on such axis.

Serving the same purpose as the strips or plates 15c and 16 in Fig. 1, are the strips 18 and 19' which may be electrically connected to each other and to the plates 15d' and 15e'.

In the method and arrangement illustrated in Fig. 3, modulation of beam 15h which corresponds to the controlled beam 15 in Fig. 1, is accomplished by deflection of the controlling beam 14c by plates 20, rather than by use of a grid for intensity-modulation of the controlling beam, as in Figs. 1 and 2. As beam 14c is deflected with respect to a fixed interceptor or blocking plate 14c', there is a corresponding change in the density of this beam to the right of plate 14c' or in other words, along that portion or length of beam 14c which is adjacent to the controlled beam 15h. The operating action, otherwise, is the same as in Fig. 1, the current output at plate 15' varying in accordance with deflection of beam 15h with respect to the intercepting edge of plate 15h'. Strips or plates 21 and 22 may be employed, as in Figs. 1 and 2.

In Fig. 4, the operating action is first a control or modulation of beam 14d by the grid 14a, and consequent deflection of beam 15i with respect to the intercepting edge of plate 15i', as in Fig. 1. The density of that portion of beam 15i to the right of plate 15i' changes accordingly, and

this portion functions as a control beam with respect to beam 15*j* and deflects the latter with respect to the intercepting edge of plate 15*j*'. That portion of beam 15*j* to the right of plate 15*j*' now functions as a control beam with respect to the next beam 15*k* and deflects the latter with respect to the intercepting edge of plate 15*k*' to vary that portion of current in beam 15*k* which reaches the output electrode 23. This method or arrangement may be extended or continued in cascade fashion, to a larger number of beams for production of multiple-beam deflections. The tube shown in Fig. 4 is, in effect, a deflection-multiplier, and since succeeding deflections increase, an enormous gain can be realized through a series of beam stages.

In the respective arrangements shown in Figs. 1, 2, 3 and 4, there may be employed focusing electrodes of known types for forming sharp beams, if desired. While the various controlling and controlled beams have been shown to be narrow, one or more of the same may, instead, be diffused and distributed over a relatively wide area.

The drawing herein is not to scale, and the walls of the glass or metal bulb or envelope of the tube device may be considered spaced considerably more from the contained parts than might be apparent from the drawing.

For practical examples of details on structure and arrangement for the respective components of the improved apparatus herein as well as an explanation of the electron optics involved, reference is made to Encyclopedia on Cathode-Ray Oscilloscopes and Their Uses, by John F. Rider and Seymour D. Uslan, and published 1950 by John F. Rider, Publisher, Inc., 480 Canal Street, New York, N. Y., and to a text book by V. K. Zworykin et al. entitled Electron Optics and the Electron Microscope, and published 1945 by John Wiley & Sons, Inc., New York, N. Y.

One of the broader aspects of the present invention resides in the fact that change of current in the controlled beam is accomplished by mechanically blocking the flow of some of this beam's electrons in amount corresponding to the controlled variation of current in the controlling beam or, as in Fig. 3, in at least part of the controlling beam. For example, by means of grid 14*a* in Fig. 1, controlled variation of the current in beam 14 is effected, and by mechanical means such as the bottom, intercepting edge of the fixed plate 15*a*, more or less of the electrons of beam 15 are blocked and thereby prevented from striking the output plate 15*b*.

In Figs. 1, 2, 3 and 4, the metal strips or plates, such as 15*c*, 16, 18, 19', and 22, respectively, establish the correct operating potentials. They also serve the additional, important purpose of shielding against otherwise troublesome effects of electrostatic charges on the walls of the envelope or bulb.

Although the output electrodes 15*b*, 15*g*, 15' and 23 have been shown as being in the form of conventional plates, they might be replaced by resonant cavities of known types; for use at the higher frequencies.

The basic principles involved in the present invention as well as several practical applications of the same, have been illustrated and described in a simplified manner for the purposes of those skilled in the art, but in addition to this it will be apparent that there are possible numerous variations such as in the size, shape and arrangement of the parts without departing from

the spirit of the invention or the scope of the claims.

What is claimed is:

1. In the art of controlling a beam of electrons, the steps which consist in generating a first beam of electrons, generating a second beam of electrons adjacent to said first beam, causing said beams to travel a substantial distance in adjacent paths to provide a cumulative mutual reaction between said beams during said travel, effecting controlled variation of the current in at least part of said first beam, and mechanically blocking the flow of some of the electrons of said second beam in amount corresponding to said variation.
2. In an electronic device of the character described, an envelope, means disposed within said envelope for generating a first beam of electrons, means disposed within said envelope for generating a second beam of electrons adjacent to said first beam, means for causing said beams to travel a substantial distance in adjacent paths to provide a cumulative mutual reaction between said beams during said travel, means associated with said first-named means for effecting controlled variation of the current in at least part of said first beam, and mechanical means disposed in said envelope in a possible path of flow of said second-named electrons as determined by occurring current-variation in said first beam.
3. In an electronic device of the character described, an envelope, means disposed within said envelope for generating a first beam of electrons, means disposed within said envelope for generating a second beam of electrons adjacent to said first beam, means for causing said beams to travel a substantial distance in adjacent paths to provide a cumulative mutual reaction between said beams during said travel, an output electrode, means associated with said first-named means for effecting controlled variation of the current in at least part of said first beam, and mechanical means disposed in said envelope between said second-named means and said electrode and in a possible path of flow of said second-named electrons as determined by occurring current-variation in said first beam.
4. In an electronic device of the character described, an envelope, means disposed within said envelope for generating a first beam of electrons, means disposed within said envelope for generating a second beam of electrons adjacent to said first beam, means for causing said beams to travel a substantial distance in adjacent paths to provide a cumulative mutual reaction between said beams during said travel, an output electrode, means associated with said first-named means for effecting controlled variation of the current in at least part of said first beam, and a plate disposed in said envelope between said second-named means and said electrode, said plate being arranged with an edge thereof effective to block the flow to said electrode of at least some of said second-named electrons as determined by occurring current-variation in said first beam.
5. In an electronic device of the character described, an envelope, means disposed within said envelope for generating a first beam of electrons, means disposed within said envelope for generating a second beam of electrons adjacent to said first beam and spaced from and substantially parallel with respect to the latter, means for causing said beams to travel a substantial distance in adjacent paths to provide

a cumulative mutual reaction between said beams during said travel, means associated with said first-named means for effecting controlled variation of the current in at least part of said first beam, and mechanical means disposed in said envelope in a possible path of flow of said second-named electrons as determined by occurring current variation in said first beam.

6. In an electronic device of the character described, an envelope, means disposed within said envelope for generating a first beam of electrons, means disposed within said envelope for generating a second beam of electrons adjacent to said first beam and spaced from and substantially parallel to the latter, means for causing said beams to travel a substantial distance in adjacent paths to provide a cumulative mutual reaction between said beams during said travel, an output electrode, grid means associated with said first-named means for effecting controlled variation of the current in at least part of said first beam, and a plate disposed in said envelope between said second-named means and said electrode, said plate being arranged with an edge thereof effective to block the flow to said electrode of at least some of said second-named electrons as determined by occurring current-variation in said first beam.

7. In an electronic device of the character described, an envelope, an output electrode, means disposed within said envelope for generating a first beam of electrons, means disposed within said envelope for generating a second beam of electrons directed at said electrode and disposed adjacent to said first beam for mutual repulsion effect between said beams, means for causing said beams to travel a substantial distance in adjacent paths to provide a cumulative mutual reaction between said beams during said travel, means associated with said first-named means for effecting density-increase of said first beam to increase said effect, and mechanical means disposed in said envelope between said second-named means and said electrode and in a possible path of flow of said second-named electrons as determined by occurring current-variation in said first beam.

8. In an electronic device of the character described, an envelope, means disposed within said envelope for generating a first beam of electrons, means disposed within said envelope for generating a plurality of beams of electrons spaced from each other and from said first beam and substantially parallel to the latter, means for causing said beams to travel a substantial distance in adjacent paths to provide between said first beam of electrons and said plurality of said beams of electrons cumulative mutual reaction during said travel, individual output electrodes for the respective beams, means associated with said first-named means for effecting controlled variation of the current in said first beam, and plates disposed in said envelope between said second-named means and certain of said electrodes, said plates being arranged with edges thereof effective to block the flow to said certain electrodes of at least some of said second-named electrons as determined by occurring current-variation in said first beam.

9. In an electronic device of the character described, an envelope, means disposed within said envelope for generating a first beam of electrons, a first interceptor plate, means for deflecting said beam with respect to an edge of said plate, an output electrode, means disposed within said en-

velope for generating a second beam of electrons adjacent and substantially parallel to said first beam, means for causing said beams to travel a substantial distance in adjacent paths to provide a cumulative mutual reaction between said beams during said travel, and a second interceptor plate disposed with an edge thereof in the path of said second beam.

10. In an electronic device of the character described, an envelope, means disposed in said envelope for generating a series of electron beams substantially parallel and spaced with respect to each other and with adjacent beams in said series disposed for mutual-repulsion effect with respect to each other, means for causing said beams to travel a substantial distance in adjacent paths to provide a cumulative mutual reaction between said beams during said travel, means for effecting variation in density of the first beam in said series, and individual and mechanical means disposed respectively in the paths of the remaining beams for blocking the latter in amounts varying in accordance with the occurring magnitudes of beam-deflection induced by said mutual-repulsion effect.

11. In the art of controlling a beam of electrons, the steps which consist in generating a first electron beam and a plurality of electron beams, disposed about and each substantially parallel to and spaced from said first beam and each disposed for mutual-repulsion effect between itself and said first beam, means for causing said beams to travel a substantial distance in adjacent paths to provide a cumulative mutual reaction between said beams during said travel, effecting variation in density of said first beam to deflect each of said plurality of beams by virtue of said mutual-repulsion effect, and mechanically blocking said plurality of beams in amounts corresponding respectively to the respective magnitudes of deflection thereof.

12. In the art of controlling a beam of electrons, generating a first electron beam, deflecting said beam, mechanically blocking said beam in amount corresponding to the magnitude of deflection thereof, generating a second electron beam adjacent to said first beam and exposed to the effect of mutual-repulsion between itself and said first beam, means for causing said beams to travel a substantial distance in adjacent paths to provide a cumulative mutual reaction between said beams during said travel, and mechanically blocking said second beam in amount corresponding to the magnitude of deflection thereof by virtue of said mutual-repulsion effect.

13. In the art of controlling a beam of electrons, generating a series of electron beams spaced from and substantially parallel to each other and each exposed to the effect of mutual-repulsion between itself and an adjacent beam, varying the density of the first beam in said series to cause deflection of the other beams in cascade fashion, and blocking said other beams individually and mechanically and in amounts varying respectively and in accordance with the respective magnitudes of beam-deflection induced by said mutual-repulsion effect.

14. In the art of controlling a beam of electrons, the steps which consist in generating a first beam of electrons, generating a second beam of electrons adjacent to said first beam, causing said beams to travel a substantial distance in adjacent paths to provide a cumulative mutual reaction between said beams during said travel, effecting controlled variation of the current in

at least part of said first beam, and blocking the flow of some of the electrons of said second beam in amount corresponding to said variation.

15. In an electronic device of the character described, an envelope, means disposed within said envelope for generating a first beam of electrons, means disposed within said envelope for generating a second beam of electrons adjacent to said first beam, means for causing said beams to travel a substantial distance in adjacent paths to provide a cumulative mutual reaction between said beams during said travel, means associated with said first-named means for effecting controlled variation of the current in at least part of said first beam, and means disposed in said envelope in a possible path of flow of said second-named electrons as determined by occurring current-variation in said first beam.
